STORAGE RACK

Kurt E. Christoffersen, Gales Ferry, Conn., assignor to Artistic Wire Products Co. of Conn., Incorporated,
Norwich, Conn., a corporation of Connecticut

Filed Nov. 1, 1960, Ser. No. 62,690

Term of patent 14 years

(Cl. D44—29)

Fig. 1 is a perspective view of a storage rack embodying my new design.

Fig. 2 is an elevational end view thereof.

Fig. 3 is a plan view of said storage rack.

Fig. 4 is an elevational side view thereof.

I claim:

The ornamental design for a storage rack, substantially as shown.
